UNITED STATES PATENT OFFICE.

HENRY PODGER, OF BROMLEY, COUNTY OF KENT, AND WILLIAM HOOK DAVEY, OF HIGHGATE, COUNTY OF MIDDLESEX, ENGLAND.

IRONING-MACHINE.

SPECIFICATION forming part of Letters Patent No. 293,514, dated February 12, 1884.

Application filed March 9, 1883. (No model.) Patented in England August 14, 1882, No. 3,867.

To all whom it may concern:

Be it known that we, HENRY PODGER and WILLIAM HOOK DAVEY, subjects of the Queen of Great Britain, residing, respectively, at 5 Bromley, in the county of Kent, and Highgate, in the county of Middlesex, England, have invented an Improved Ironing-Machine, (for which we have received Letters Patent in Great Britain, No. 3,867, dated August 14, 10 1882,) of which the following is a specification.

Our invention relates to an improved ironing-machine which is especially adapted for ironing shirt-fronts, collars, cuffs, and fancy articles.

15 The invention consists, mainly, in the combination, with a vertically-adjustable and horizontally-movable table, of a longitudinally-reciprocating iron.

It also consists in a gas-heated iron which is 20 double-faced and reversible, so that the one face is being heated while the other is being used. The ironing-table is supported on a bed which is movable vertically, in order to bring the table up to the iron and apply the necessary pressure to the goods, and is also movable 25 horizontally in a circular direction, in order to present the goods in the desired direction to the iron; and the table is also movable in a rectilinear direction on this bed, to permit 30 of the goods being moved to and fro under the iron. The iron may or may not be reversible; but when reversible it is hung on end gudgeons, one (or both) of which is tubular to admit gas; and the iron has two faces 35 on opposite sides, so that one is upward being heated, while the other is downward and is getting cold in use.

Figure 1 is a side elevation, Fig. 2 an end elevation, and Fig. 3 a plan, of the improved 40 ironing-machine, the example here represented being constructed double, so as to carry two irons and two ironing-tables on the same framing; but it may also be made single, as will be readily understood.

45 A are two cast-iron frames or standards, suitably braced together by the guide-brackets B for the beds of the ironing-tables. These frames are constructed with horizontal arms A', braced together at the extremities by the 50 bolts upon which the guide-rollers hereinafter referred to turn.

C are cast-iron beds for the ironing-tables, fixed upon vertical guide-rods c, capable of sliding up and down and of turning in guide-collars b, carried by the brackets B.

55 D are the ironing-tables, also of cast-iron, and faced with a pad of any suitable fabric. Each table has two parallel ribs or rails, d, on its under side, which run in the grooves of pairs of grooved rollers E, fast on spindles e, 60 lying across the bed C, and resting and turning in grooves therein. By these rails and rollers the table is guided in its horizontal rectilinear motion, while the table and its bed are caused to turn together. Each table and its bed are 65 supported, raised, and lowered by a treadle, F, working on a fixed pivot at f, and connected by a link to the end of a lever, G, pivoted at g to a fixed standard, and forked at its other end, and embracing the guide-rod c between collars c', fixed thereon.

70 H are the irons, which are represented in Figs. 1, 2, and 3 as single-faced. They are hung from a guide-rod, I, which, in the case of a double machine, carries both irons, and 75 extends across and beyond the ends of the two arms A' of the frame. This guide-rod I runs to and fro between pairs of grooved guiding-rollers K above and beneath it, these 80 rollers running loose upon the bolts k, which brace the pairs of frames A together.

L is the driving-shaft with fast and loose 85 pulleys and a disk carrying a crank-pin, l, which is coupled by a connecting-rod, M, to the rod I.

The irons are represented as heated by steam supplied and exhausted through a pair of pipes, S S', connected to the irons and to flexible pipes s' s', leading up or down to fixed main supply and exhaust pipes.

90 The construction of a single-iron machine will be obvious without further drawings.

Fig. 4 is a longitudinal sectional elevation of a reversible gas-heated iron. Fig. 5 is an end view, and Fig. 6 a cross-section, of the iron. 95 The iron is a casting of box form, inclosed by two steel ironing-faces, H' H'', and is hung by end journals, h h', in the arms of a frame fixed to rod I, as before. The journal h' is tubular, and into it is screwed a perforated pipe, N, forming the gas-burner. This burner turns with the iron, and is perforated at

the sides, so as to answer either way up. A gas-pipe, P, of smaller diameter than the bore of the journal h', projects concentrically thereto, so as to leave an annular inlet for air, 5 thus constituting an atmospheric burner. The gas-pipe P is supported by any suitable frame from the guide-rod I, and is connected to a flexible supply-pipe, p, so as to move to and fro with the irons without being connected 10 therewith, leaving the irons quite free to turn independently of the gas-pipe.

R is a disk fixed on the journal h, having two recesses, r, with either of which engages a locking-lever, T, pivoted at t to the frame 15 to lock the iron in position.

x are air-holes.

Having described the nature of the said invention and the manner of performing the same, we declare that what we claim is—

20 1. In an ironing-machine, the combination, with an iron and means for reciprocating the same horizontally, of a bed mounted substantially as described, whereby it may be rotated and moved vertically, and a table, said table 25 and bed being constructed substantially as set forth, whereby the table may be moved transversely on the bed, as and for the purpose specified.

2. In an ironing-machine, the combination, 30 with the frame, the irons, and means for reciprocating them horizontally, of the bed C, having guide-rods c, journaled in brackets of the frame, and provided with the grooved rollers E, the table D, provided with the ribs or 35 rails d, and means for raising and lowering said bed, substantially as herein shown and described.

3. In an ironing-table, the combination, with the frame A, having the brackets B B, of

the bed C, provided with the guide-rod c, mounted vertically in the said brackets, and provided with the collars b c', the treadle F, the lever G, connected to the treadle at one end, and the other end embracing the guide-rod c, and the table D, the said table and bed being constructed as set forth, whereby the former may be moved laterally upon the bed, substantially as shown and described. 40 45

4. In an ironing-machine, the combination, with the frame A A', provided with the guide-rollers K K, the guide-rod I, and means for operating said guide-rod, of the double-faced iron H', having the hollow journal h', and journaled in hausers on the bar I, the burner N, and means for locking the iron in position, 50 substantially as herein shown and described. 55

5. In an ironing-machine, the combination, with journaled and double-faced iron H', provided with the hollow journal h', of the burner N, secured within the iron, and provided 60 with side perforations, substantially as herein shown and described.

6. In an ironing-machine, the combination, with the journaled and double-faced iron H', and the burner N within said iron, of the disk 65 R, secured to the journal h of the iron, and provided with the recesses r, and the locking-lever t, substantially as herein shown and described.

The above specification of our invention signed by us this 30th day of January, A. D. 70 1883.

HENRY PODGER.
WILLIAM HOOK DAVEY.
